Des. 182,208

Patented Feb. 25, 1958

182,208

RACK FOR TOWELS AND THE LIKE

Clarence Sova, Windsor, Ontario, Canada

Application March 15, 1956, Serial No. 40,639

Term of patent 14 years

(Cl. D4—3)

I claim:

The ornamental design for a rack for towels and the like, as shown.
